UNITED STATES PATENT OFFICE.

JOSEPH T. ROFFY, OF PITTSBURGH, PENNSYLVANIA.

DESIGN FOR A BLOWN-GLASS HEADLIGHT-REFLECTOR.

59,930.

Specification for Design: Patented Dec. 6, 1921.

Application filed March 7, 1921. Serial No. 450,483. Term of patent 14 years.

To all whom it may concern:

Be it known that I, JOSEPH T. ROFFY, a subject of the Republic of Hungary, and residing at Pittsburgh, in the county of Allegheny and State of Pennsylvania, have invented a certain new, original, and ornamental Design for a Blown-Glass Headlight-Reflector, of which the following is a specification, reference being had to the accompanying drawing, forming a part there-

of, Figure 1 of which is a front view, Fig. 2 is a vertical section taken at the center of the reflector, and Fig. 3 is a back view of the same.

I claim:—

The ornamental design for a blown glass headlight reflector, substantially as shown.

JOSEPH T. ROFFY.

Witness:

FRANCES B. BENTZ.
